His atty.

UNITED STATES PATENT OFFICE.

WILLIAM GRAH, OF WATERVILLE, OHIO.

AUDIBLE LOW-LIQUID-LEVEL ALARM FOR TANKS.

1,381,299.

Specification of Letters Patent. Patented June 14, 1921.

Application filed May 6, 1920. Serial No. 379,232.

To all whom it may concern:

Be it known that I, WILLIAM GRAH, a citizen of the United States, and a resident of Waterville, in the county of Lucas and State of Ohio, have made an Invention Appertaining to Audible Low-Liquid-Level Alarm for Tanks; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to audible alarms for use particularly in connection with the liquid containing tanks of automobiles to indicate a predetermined low liquid level therein.

The object of the invention is the provision of an improved simple and efficient signal or alarm means of the class described which is operable by movements of the vehicle to sound an audible alarm when the liquid in the container is at a predetermined low level therein, and is prevented by the liquid from sounding an alarm when the liquid is above said level.

The invention is fully described in the following specification, and while, in its broader aspect, it is capable of embodiment in numerous forms, a few only of such forms are illustrated in the accompanying drawings, in which,

Figure 1 is a vertical section of a liquid container equipped with one form of the invention with the liquid therein at low level point and the signal means operative. Fig. 2 is a similar view of another modification of the device in which the signal means is disposed entirely within the container.

Referring to the drawings, 1 designates a liquid tank or container, for instance the gasoline tank of an automobile, having the opening 2 in its top through which the tank may be filled, which opening is closed by a removable cap 3. Suspended through the opening from the cap 3, or in any other suitable manner, down into the tank is a bell, gong or other resonant member 4, the suspending means therefor, in the present instance, comprising a sectional rod 5 having the sections thereof connected by a turn buckle 6 to facilitate a vertical adjustment of the resonant member 4 within the tank.

A striker 5 is suspended within the resonant member 4, for free swinging movements therein, by a chain or other flexible member 7. Attached to the lower end of the striker 5 is a float 8, which is movable up into the resonant member 4 by a raising of the level of the liquid in the tank and thereby prevents the striker from swinging into striking contact with the bell or member 4. When the level of the liquid within the tank has lowered a predetermined extent the striker 5 is free to swing into striking contact with the member 4 and thereby sound an audible alarm which will indicate the low level of the liquid. The swinging movement of the striker to sound the alarm is caused by the motion of the vehicle with which the tank is associated and for this reason the member 4 should be rigidly carried by the tank to respond to the vibrations thereof.

In the form of the invention illustrated in Fig. 2, the gong or resonant member 15 is suspended within the tank from the cap 3^a by a tube 16, which has its interior in communication at its lower end with the interior of the gong 15 through a centrally disposed tube or passageway 17. The upper end of the tube 16 is threaded or otherwise suitably secured in a socket 18 in the under side of the cap 3^a and this socket has an opening 19 through the cap to the outer side thereof. A gate valve 20 is hinged within the socket 18 at one side of the opening 19 for opening and closing movements relative to said opening. A rod 21 extends down from the valve 20 through the tubes 16 and 17 and carries a striker 22 within the gong or resonant member 15, the striker being swingingly connected to the rod by a link 23. A float 24 is attached to the lower end of the striker 22 and this float when resting on the liquid within the tank prevents a swinging of the striker into audible striking contact with the gong. When the level of the liquid is raised from the alarm sounding point the float effects a raising of the connections between it and the valve 20 and a closing of said valve so that if there should be a slight tapping of the striker against the gong by reason of the lateral movements of the float with the liquid the sound will not be carried without the tank. When the valve 20 is open and the gong is struck the alarm is distinctly audible without the tank. In this form of

the invention both the tube 16 and rod 21 are longitudinally adjustable to suit the height at which it is desired to place the gong and float member within the tank.

5 It is evident in each form of the invention that one of the alarm members, the striker in the present instance, is raised or lowered by a float member into operative and inoperative relation to the other member, and that when the liquid is above a predetermined low level in the tank the alarm means will be held inoperative by the float member. It will be understood, however, that while in each form illustrated a 15 float is shown in connection with the striker member, such float may be omitted as the submergence of the striker member itself in the liquid will prevent the member from striking against the gong or resonant member with sufficient force to sound an alarm. 20 As soon as the liquid would lower below the striker member, such member would be free to swing into alarm sounding contact with the gong.

25 I wish it understood that my invention is not limited to any specific construction, arrangement or form of the parts, as it is capable of numerous modifications and changes without departing from the spirit 30 of the claims.

Having thus described my invention, what I claim as new, and desire to secure by Letters Patent, is,—

35 1. In a motor vehicle, a liquid containing tank, an audible alarm device associated therewith and including a bell with a swinging clapper, and a float suspended from the clapper for swinging movements therewith.

and adapted to coact with the clapper to prevent the sounding of an alarm except when 40 the liquid is at or below a predetermined low level in the tank.

2. In a vehicle, a liquid containing tank, a resonant member suspended within the tank and having a passageway extending 45 therefrom to without the tank, a gate for closing said passageway, a striker for the resonant member and connected to said gate, and a float operable to close the gate and to render the striker member inoperative when 50 the liquid is above a predetermined level in the tank.

3. In a vehicle, a liquid containing tank having an opening in its upper portion, an alarm device within the tank adapted to 55 sound an alarm when the liquid in the tank lowers below a predetermined level, a valve for closing the tank opening, and means automatically operable to open the valve when the liquid in the tank has lowered a 60 predetermined extent.

4. In a vehicle, a liquid containing tank having an opening in its top, a cap for removably closing said opening and having an opening therein, an audible alarm means suspended from the cap through the tank opening and operable to sound an alarm when the liquid in the tank lowers below a predetermined level, a valve for closing the cap opening, and float operated means for operating 70 the valve to close the cap opening when the liquid is above a predetermined level, and vice versa.

In testimony whereof I have hereunto signed my name to this specification.

WILLIAM GRAH.
